UNITED STATES PATENT OFFICE.

JAMES G. McNAMARA, OF BROOKLYN, NEW YORK, ASSIGNOR TO MERGENTHALER LINOTYPE COMPANY, A CORPORATION OF NEW YORK.

TYPGRAPHICAL MACHINE.

Application filed May 8, 1924. Serial No. 711,772.

This invention relates to typographical machines, such as linotype machines of the general organization represented in Letters Patent of the United States, No. 436,532 to O. Mergenthaler, wherein circulating matrices are released from a magazine in the order in which their characters are to appear in print and then assembled in line, the composed line transferred to the face of a mold, the mold filled with molten metal to form a slug or linotype against the matrices which produce the type characters thereon, and the matrices thereafter elevated and returned through distributing mechanism to the magazine from which they started. More particularly, it relates to machines equipped with a plurality of magazines containing different matrix fonts and which are arranged to be moved upwardly and downwardly in the machine to bring one or another into operative relation to the assembling and distributing mechanisms.

The present invention is directed to certain improvements in machines of the class stated intended to simplify the construction and to facilitate the independent removal and application of the several magazines, and this without disturbing the matrix releasing escapements which remain in the machine at all times to cooperate with whatever magazines are for the time being in use. These improvements will best be understood from the detailed description to follow.

While as above stated, the invention is intended for use more particularly in machines equipped with a plurality of shiftable magazines, it is also applicable to machines of the single magazine variety.

Referring to the drawings:

Fig. 1 is a perspective view of a portion of a linotype machine equipped with the invention, the top magazine of the series being omitted;

Fig. 2 is a side elevation of the magazine structure and showing the magazines spread apart and the middle magazine in process of removal;

Fig. 3 is a top plan view of one of the magazine base frames with its magazine removed;

Fig. 4 is a longitudinal section taken on the line 4—4 of Fig. 3;

Fig. 5 is a vertical section taken on the line 5—5 of Fig. 4; and

Fig. 6 is a perspective view of the magazine lifting cam.

The matrices are stored according to font in the superposed channeled magazines A, three of which are shown herein but of which a greater or less number might be employed if desired. The several magazines are removably supported upon separate base frames A' conjointly constituting a shift frame which is arranged to be moved upwardly and downwardly in the fixed machine frame in the well known manner to bring any selected magazine into operative relation to the assembling mechanism B at the lower end and the distributing mechanism C at the upper end. Each of the magazines is provided with a series of matrix releasing escapements D (Fig. 4) which, when the magazine is brought into operative position, are actuated under the control of the keyboard mechanism in the usual way. In the present instance, the two upper base frames A' are pivoted at their upper ends, as at A², to a pair of plates A³ rising from the lowermost base frame, so that the base frames and their respective magazines may be separated or spread apart to permit the independent removal of any selected magazine. Such separation of the magazines is effected by means of a hand lever J fixed to a transverse rock shaft J' journaled in the lowermost base frame and provided at its opposite ends with arms J² connected by links J³ to the uppermost base frame, which latter has suspended therefrom a pair of lifting links J⁵ connected to the middle base frame. When in use, the magazines and base frames occupy the close parallel relation shown in Fig. 1, but when one of the magazines is to be removed, the handle J is drawn forwardly to cause the parts to occupy the spread apart relation shown in Fig. 2. The foregoing parts and their mode of operation are or may be substantially as embodied in the commercial Model 8 linotype or as illustrated in the Kennedy Patent No. 1,396,125, to which reference may be had for any further details.

According to the present invention, the bank of escapements for each magazine is mounted in a fixed or set position upon the corresponding base frame, and means are provided for lifting the magazine from the base frame to disengage it from the escapement bank preparatory to its removal or re-

placement, such lifting means being preferably constructed to support the magazine in its elevated position and to guide it in a straight path as it is drawn forwardly from the front of the machine.

As best shown in Fig. 4 each bank of escapements D is mounted in the usual manner in a supporting bar or frame D', which frame (see Fig. 3) is screwed or otherwise fastened to the lower end of the corresponding base frame A'. As ordinarily, the magazines are formed on their undersides with transverse slots or openings to receive the escapement bars, the latter being formed on their upper sides with grooves which extend across the magazine openings and constitute in effect continuations of the grooves in the bottom plates of the magazines. Such being the relation of the parts, it is apparent that before a magazine can be removed, it must first be disengaged from its escapement bank. For this reason, each base frame is provided with a central magazine lifting and supporting plate E, which in the present instance is substantially as long as the base frame itself and which is located in a corresponding groove or recess E' formed in the upper side of the base frame. At its upper end, the plate E is pivoted to the base frame by means of a pair of hinge pins E² which thus permit it to be swung upwardly in lifting the magazine; and at its lower end, it is provided with stop shoulders E³ normally engaged with the customary forward transverse rib a on the underside of the magazine and which thus retain the magazine in place on the plate when the latter is in its raised position. The magazine lifting and supporting plate is also formed throughout its length with a groove E⁴ wherein engages the customary longitudinal rib a' on the underside of the magazine and which acts as a guideway for the magazine as it is drawn forwardly from the machine.

In the embodiment illustrated, the swinging of the magazine lifting and supporting plate of each base frame is controlled and effected by a cam or equivalent device F arranged near the lower end thereof and fast to a transverse rock shaft F' journaled in the base frame. This cam (Fig. 6) is provided with a notched or hook shaped piece F² adapted, when the cam is turned upwardly, to engage a pin F³ on the edge of the plate E and thus lock the latter in its proper raised position. The cam is limited in its downward movement by a stop pin F⁴ on the base frame, the plate E in its lowered position resting upon the base frame at the bottom of the containing groove E¹.

The operation of the cam shafts F' may be effected in any desired manner, but it is proposed to employ for the purpose the usual magazine supporting arms G. As

shown these arms G are provided with bosses G' adapted to be applied to the opposite ends of the cam shaft of any selected base frame, it being noted that the rock shafts are slotted at their outer ends to receive cross pins G² passed through the bosses G'. By means of such pin and slot engagement, the magazine supporting arms may be readily applied to or removed from the required cam shaft and, when applied, serve as handles or cranks for turning it in one direction or the other. In the operative position of the magazine supporting arms as shown in Figs. 2 and 3, they rest at their inner edges upon the opposite ends of the appropriate escapement bar D', the latter being provided with pins D² which enter corresponding apertures in the arms and prevent their accidental disconnection from the cam shaft. In removing a selected magazine, the supporting arms are applied to the corresponding cam shaft F' in a position substantially at right angles to the magazine and are then drawn downwardly to their magazine supporting position, which action effects the turning of the cam shaft and the lifting of the magazine from the base frame as just described. The magazine is then slightly tilted at its forward end to disengage its front rib a from the stop shoulders E³ and slid forwardly along the plate E onto the supporting arms as indicated by the dotted lines in Fig. 2, the magazine being guided in its forward sliding movement by the engagement of its central longitudinal rib a' with the groove or guideway E⁴. The magazine is provided on its underside, as shown, with additional transverse ribs which enable it to be arrested in different longitudinal positions on the lifting and supporting plate when desired. To prevent any possible injury to the escapements and to assist in supporting the magazine during its removal, the escapement bars D' are each formed at opposite ends with upstanding projections D³ and D⁴ arranged substantially at the level of the track portions of the magazine supporting arms.

It will be observed that when the magazines are elevated out of engagement with their corresponding escapements, the contained matrices would be free to pass therefrom unless they were first locked therein, and hence means are provided to prevent the operation of the cam shafts until the matrices have been locked in the magazine. In the present instance (see particularly Figs. 3 and 4) such means comprise, for each magazine, a centrally pivoted latch H mounted in the left hand projection D² of the escapement bar, and upright arm H' fast to the end of the cam shaft F'. The latch is normally held in the path of the arm by a spring H² so as to lock the cam shaft against rotation, but the latch is arranged to be disengaged

from the arm by the usual matrix locking rod H^3 which is inserted through the edge of the magazine in the customary way. This matrix locking rod, as it is pushed home, engages the front end of the locking latch and rocks it against the action of the spring H^2 clear of the shaft arm H' . When the matrices are thus locked in the magazine, the cam shaft is free to be rotated to swing the magazine upwardly out of engagement with the escapements preparatory to removal. In place of the detachable matrix locking rod H^3 , the magazines may be provided with permanent locking rods, such as shown and described in the Kennedy Patent No. 1,347,638, which are shiftable in an endwise direction to lock or unlock the matrices.

It is believed that the operation of the parts will be entirely clear from the foregoing description. However to recapitulate, it may be stated that in removing any selected magazine, the matrix locking rod H^3 is first inserted through the edge of the magazine in the manner just described, and then the supporting arms G are applied to the cam shaft F' and drawn downwardly to swing the plate E upwardly and lift the magazine out of engagement with the escapements, all as indicated by the full lines in Fig. 2. The magazine is then free to be slid forwardly onto the supporting arms and removed in the customary way, as indicated by the dotted lines in Fig. 2. In substituting a new magazine, the above operations are simply reversed, that is to say, after sliding the substitute magazine back onto the lifting and supporting plate E , the supporting arms G are thrown upwardly to lower the magazine into engagement with the escapements, which of course remain in place upon the base frame, and the matrix locking rod H^3 then withdrawn to permit the matrices to be released from the magazine when in use. In the present instance, the magazines are spread apart by the operation of the hand lever J to facilitate the removal of the two lower magazines, but this of course would not be necessary if the space between the magazines were great enough to permit the required lifting of an underlying magazine without interference with the overlying magazine. The employment of the magazine separating means is advantageous, in that the magazines and their base frames may be arranged in close compact relation as shown in Fig. 1.

In the accompanying drawings the invention has been shown merely in preferred form and by way of example and as applied to a machine of the class stated, but obviously many modifications and alterations may be made therein without departing from the spirit of the invention. It should be understood therefore that the invention is not limited to any specific form or embodiment ex-

cept in so far as such limitations are specified in the appended claims.

Having thus described my invention, what I claim and desire to secure by Letters Patent of the United States, is as follows:

1. In a typographical machine, the combination of the main frame, a matrix magazine, a base frame movably mounted in the main frame and upon which the magazine is removably supported, a bank of escapements mounted upon the base frame in operative engagement with the magazine, and means for lifting the magazine from the base frame to disengage it from the escapement bank preparatory to its removal or replacement. 75

2. In a typographical machine, the combination of the main frame, a matrix magazine, a base frame movably mounted in the main frame and upon which the magazine is removably supported, a bank of escapements mounted upon the base frame in operative engagement with the magazine, and a magazine lifting and supporting plate pivoted to the base frame and adapted to be swung upwardly to disengage the magazine from the escapement bank preparatory to its removal or replacement. 85 90

3. In a typographical machine, the combination of the main frame, a matrix magazine, a base frame movably mounted in the main frame and upon which the magazine is removably supported, a bank of escapements mounted upon the base frame in operative engagement with the magazine, a magazine lifting and supporting plate pivoted to the base frame near the upper end thereof, and means arranged at the lower end of said plate for swinging it upwardly about its pivot. 95 100 105

4. In a typographical machine, the combination of the main frame, a matrix magazine, a base frame movably mounted in the main frame and upon which the magazine is removably supported, a bank of escapements mounted upon the base frame in operative engagement with the magazine, a magazine lifting and supporting plate pivoted to the base frame near the upper end thereof, a rock shaft journaled in the base frame near the lower end thereof, and a cam fast to said rock shaft and arranged to engage the lower end of the magazine lifting and supporting plate. 110 115

5. In a typographical machine, the combination of the main frame, a matrix magazine, a base frame movably mounted in the main frame and upon which is removably supported, a bank of escapements mounted upon the base frame in operative engagement with the magazine, and a magazine lifting and supporting plate arranged to be swung upwardly to disengage the magazine from the escapement bank preparatory to its removal or replacement, the said plate 120 125 130

being provided with means to hold the magazine in place thereon when in its lifted position.

6. In a typographical machine, the combination of a matrix magazine, a base frame upon which it is removably supported, a bank of escapements mounted upon the base frame in operative engagement with the magazine, and a magazine lifting and supporting plate arranged to be swung upwardly to disengage the magazine from the escapement bank preparatory to its removal or replacement, the said plate being provided with a magazine guideway running lengthwise thereof.

7. In a typographical machine, the combination of a matrix magazine, a base frame upon which it is removably supported, a bank of escapements mounted upon the base frame in operative engagement with the magazine, and a magazine lifting and supporting plate arranged to be swung upwardly to disengage the magazine from the escapement bank preparatory to its removal or replacement, the said plate being provided with a magazine guideway running lengthwise thereof and stop shoulders to retain the magazine in place thereon.

8. In a typographical machine, the combination of a matrix magazine, a base frame upon which it is removably supported, a bank of escapements mounted upon the base frame in operative engagement with the magazine, means for lifting the magazine from the base frame to disengage it from the escapement bank preparatory to its removal or replacement, means for locking the matrices in the magazine, and means for preventing the lifting of the magazine until the matrices have first been locked therein.

9. In a typographical machine, the combination of a matrix magazine, a base frame upon which it is removably supported, a bank of escapements mounted upon the base frame in operative engagement with the magazine, a magazine lifting and supporting plate pivoted to the base frame and adapted to be swung upwardly to disengage the magazine from the escapement bank preparatory to its removal or replacement, means for locking the matrices in the magazine, and means for preventing the upward swinging of the magazine lifting and supporting plate until the matrices have first been locked in the magazine.

10. In a typographical machine, the combination of a matrix magazine, a base frame upon which it is removably supported, a bank of escapements mounted upon the base frame in operative engagement with the magazine, a magazine lifting and supporting plate pivoted to the base frame near the upper end thereof, a rock shaft journaled in the base frame near the lower end thereof, a cam fast to said rock shaft and arranged to

engage the lower end of the magazine lifting and supporting plate, a movable rod to lock the matrices in the magazine, and a safety catch controlled by said matrix locking rod to prevent the operation of the cam shaft at 70 an improper time.

11. In a typographical machine, the combination of a matrix magazine, a base frame upon which it is removably supported, a bank of escapements mounted upon the base frame in operative engagement with the magazine, a magazine lifting and supporting plate pivoted to the base frame near the upper end thereof, a rock shaft journaled in the base frame near the lower end thereof, a cam fast to said rock shaft and arranged to engage the lower end of the magazine lifting and supporting plate, and a pair of magazine supporting arms adapted to be applied to the opposite ends of said cam 80 shaft for rotating it to effect the upward swinging of the magazine lifting and supporting plate.

12. In a typographical machine, the combination of a matrix magazine, a base frame upon which it is removably supported, a bank of escapements mounted upon the base frame in operative engagement with the magazine, a magazine lifting and supporting plate pivoted to the base frame near the upper end thereof, a rock shaft journaled in the base frame near the lower end thereof, a cam fast to said rock shaft and arranged to engage the lower end of the magazine lifting and supporting plate, a pair of magazine supporting arms adapted to be applied to the opposite ends of said cam shaft for rotating it to effect the upward swinging of the magazine lifting and supporting plate, and pins or similar devices arranged to engage the magazine supporting arms in their operative position to prevent their accidental displacement from the cam shaft.

13. In a typographical machine, the combination of a matrix magazine, a base frame upon which it is removably supported, a bank of escapements mounted upon the base frame in operative engagement with the magazine, a magazine lifting and supporting plate pivoted to the base frame and adapted to be swung upwardly to disengage the magazine from the escapement bank preparatory to its removal or replacement, and a pair of upstanding projections associated with the escapement bank to give support to the magazine during its removal thereover.

14. In a typographical machine, the combination of a plurality of matrix magazines, a shift frame therefor comprising a plurality of base frames upon which the respective magazines are removably supported, escapement banks mounted upon the respective base frames in operative engagement with the magazines, and means carried by each base frame for lifting the correspond- 130

ing magazine therefrom to disengage it from the escapement bank preparatory to its removal or replacement.

15. In a typographical machine, the combination of a plurality of matrix magazines, a shift frame therefor comprising a plurality of base frames upon which the respective magazines are removably supported, escapement banks mounted upon the respective base frames in operative engagement with the magazines, and a magazine lifting and supporting plate pivoted to each base frame and adapted to be swung upwardly to disengage the corresponding magazine 10 from the escapement bank preparatory to its removal or replacement.

16. In a typographical machine, the combination of a plurality of matrix magazines, a shift frame therefor comprising a plurality of base frames upon which the respective magazines are removably supported, escapement banks mounted upon the respective base frames in operative engagement with the magazines, a magazine lifting and 20 supporting plate pivoted to each base frame near the upper end thereof, and means carried by each said base frame near the lower end thereof for swinging said plate upwardly about its pivot.

30 17. In a typographical machine, the combination of a plurality of matrix magazines, a shift frame therefor comprising a plurality of base frames upon which the respective magazines are removably supported, escapement banks mounted upon the respective base frames in operative engagement with the magazines, a magazine lifting and supporting plate pivoted to each base frame near the upper end thereof, a rock shaft 35 journaled in each said base frame near the lower end thereof, and a cam fast to each such rock shaft and arranged to engage the lower end of the associated magazine lifting and supporting plate.

40 45 18. In a typographical machine, the combination of a plurality of matrix magazines, a shift frame therefor comprising a plurality of base frames upon which the re-

spective magazines are removably supported, escapement banks mounted upon the respective base frames in operative engagement with the magazines, means carried by each base frame for lifting the corresponding magazine therefrom to disengage it from the escapement bank preparatory to its removal or replacement, matrix locking means for each magazine, and means associated with each base frame for preventing the lifting of its magazine until the matrices have first been locked therein.

19. A combination as specified in any one of claims 14 to 18, and including as an additional element means for separating the base frames from each other to facilitate the removal of the magazines.

20. In a typographical machine, the combination of a shift frame, a plurality of independently removable matrix magazines carried by said frame, a corresponding plurality of escapement banks mounted in the shift frame in operative engagement with the magazines, and means carried by the shift frame in association with each magazine for lifting the individual magazines out of engagement with their corresponding escapement banks preparatory to removal or replacement.

21. In a typographical machine, the combination of a shift frame, a plurality of independently removable matrix magazines carried by said frame, a corresponding plurality of escapement banks mounted in the shift frame in operative engagement with the magazines, means carried by the shift frame in association with each magazine for lifting the individual magazines out of engagement with their corresponding escapement banks preparatory to removal or replacement, means for locking the matrices in each magazine, and means for preventing the lifting of a magazine out of engagement with its escapement bank until the matrices have first been locked therein.

In testimony whereof, I have affixed my signature hereto.

JAMES G. McNAMARA.
